JERSEY.

SNAPPING ROLLS FOR HUSKERS AND SHREDDERS.

1,418,424.

Specification of Letters Patent. Patented June 6, 1922.

Application filed February 27, 1919. Serial No. 279,617.

To all whom it may concern:

Be it known that we, BERT R. BENJAMIN and GEORGE M. MERWIN, citizens of the United States, and residents, respectively, 5 of Oak Park, in the county of Cook and State of Illinois, and of Berwyn, in the county of Cook and State of Illinois, have invented certain new and useful Improvements in Snapping Rolls for Huskers and 10 Shredders, of which the following is a full, clear, and exact specification.

This invention relates to snapping rolls.

It is common in corn handling machines such as corn pickers and corn huskers and 15 shredders, to use coacting rolls to snap the ears from the stalks. It is also common to use snapping rolls having longitudinal grooves or corrugations therein in order to more firmly grip the stalks and feed the 20 stalks through the rolls.

When corrugated rolls are used, in certain instances the ears of corn have been fed through the rolls without being snapped from the stalks, since the ears have in such 25 instances been carried through the rolls in the longitudinal grooves. It has also been found that pieces of the stalks (and more particularly when the stalks are wet), have become lodged in the grooves, preventing 30 the proper feeding action.

Another difficulty that has been experienced in the use of such corrugated rolls in huskers and shredders, is that the cutter, which in such machines is positioned immediately beyond and close to the rolls, has at 35 times engaged the longitudinal ribs, thereby seriously injuring the machine.

With these difficulties in mind, the object of the present invention is to provide a 40 snapping roll having the advantages of the corrugated rolls, but eliminating the disadvantages.

This has been done in the present instance by providing means for breaking up the 45 longitudinal grooves into a series of comparatively short grooves and by providing means in the grooves for preventing the engagement of the cutter with the longitudinal ribs.

One embodiment of the invention is illustrated in the accompanying drawing, and in this drawing,—

Figure 1 illustrates in elevation a pair of snapping rolls having our invention embodied therein;

Fig. 2 is an elevational view on an enlarged scale showing more clearly the improved construction; and

Fig. 3 is a view of the construction shown in Fig. 2 and taken at right angles thereto. 60

As illustrated in the drawings, the snapping rolls 10 are provided with a series of longitudinal grooves 11 and 12 in their outer peripheries. The grooves 11 are symmetrical as shown in Fig. 3, whereas the 65 grooves 12 have one straight side. This construction was adopted to facilitate the drawing of the pattern of the roll from the mold, these rolls being preferably constructed of cast iron. It should be understood, however, that all of the longitudinal grooves may be formed symmetrical if desired, and that the particular shape of the 70 grooves 12 has been adopted merely for convenience, and is not vital to the success 75 of the invention but, while not essential, is embodied in the preferred form of my invention.

The longitudinal grooves are provided with beveled end walls 13 and each of these 80 grooves is provided with a plurality of cross ribs or webs 14 provided with beveled sides 15. The object in making the sides of the cross ribs and the end walls of the grooves beveled is to facilitate the molding of the roll 85 and also to more readily prevent any wet stalks from becoming lodged in the grooves.

As shown in Figs. 1 and 2, the cross ribs on one groove are staggered with respect to the cross ribs in the adjacent groove in 90 order to present a more continuous peripheral surface, thereby preventing the engagement of a cutter knife with the grooves of the snapping roll. The cross ribs are so spaced in the longitudinal grooves that the 95 distance between two successive ribs is less than the length of the average ear of corn, and this being true it will be readily seen that there is no possibility of an ear lying in one of the grooves between two ribs and being fed in this way through the rolls without being snapped from the stalk.

As shown in Fig. 3, we prefer to mount the coacting rolls on their shafts in such a manner that the longitudinal ribs on one roll will be disposed opposite the grooves on the coacting roll. This prevents the grooves of one roll from coming opposite the grooves of the adjacent roll and thereby renders the feeding action of the rolls more positive and 100 105 110

decreases the liability of an ear of corn being fed through the rolls without being snapped from the stalks.

We have not illustrated in the drawings 5 any particular mounting for the rolls since any of the common forms of mounting may be used, the usual practice being to provide a spring mounting for the upper roll wherein the springs are utilized to press this roll 10 toward the lower roll.

From the above description it will be seen 15 that we have provided a construction of snapping roll having the positive feeding action of the corrugated snapping roll, but having the advantage of preventing the ears and stalks from becoming lodged in the corrugations and preventing the ears from being fed through the rolls without being snapped from the stalks. By locating the 20 cross ribs as shown in the drawings, that is, in staggered relation, the roll is provided with a more nearly continuous peripheral surface and the liability of engagement of the cutter with the longitudinal corruga- 25 tions is greatly reduced.

While we have in the above specification shown and described but one embodiment of our invention, it is to be understood that we do not intend to be limited to the exact construction illustrated, but that various modifications may be employed without departing 30 from the spirit and scope of the invention as expressed in the following claims:

1. A snapping roll having a series of elongated longitudinally extending grooves 35 formed in its periphery and extending substantially the entire length of the roll, the end walls of said grooves being beveled outwardly from the bottom, each of said grooves having a plurality of relatively narrow cross ribs or webs therein whereby said elongated 40 grooves are subdivided into a plurality of comparatively short grooves, the outer edges of the ribs being continuous with the cylindrical surface of the rolls.

2. A snapping roll having a series of elongated longitudinally extending grooves 45

formed in its periphery parallel to the axis of the roll and extending substantially the length thereof, each of said grooves having 50 a plurality of narrow cross ribs therein having beveled side walls whereby said elongated grooves are subdivided into a plurality of comparatively short grooves having outwardly flaring ends. 55

3. A snapping roll having a plurality of longitudinal grooves formed in its periphery, said grooves having beveled end walls, each of said grooves having a plurality of closely spaced cross ribs therein, said ribs having 60 beveled side walls, the outer edges of the end walls and ribs being substantially at right angles to the grooves.

4. In a husker, a pair of cooperating snapping rolls, each roll having a series of elongated longitudinally extending grooves alternating with cylindrical portions or longitudinal ribs, transverse webs dividing each groove into a plurality of relatively short grooves, the edges of the transverse webs being continuous with the cylindrical surface of the longitudinal ribs and arranged in staggered relation in adjacent grooves, the grooves in each roll being opposed to and cooperating with the cylindrical portion of the other roll. 65 70 75

5. A snapping roll having a plurality of parallel grooves in its periphery, one of the grooves being symmetrical with respect to a diameter passing therethrough and the adjacent grooves being asymmetrical. 80

6. A snapping roll having a plurality of longitudinally extending parallel grooves alternating with a plurality of parallel ribs, webs dividing the grooves into a plurality of relatively short grooves, two opposite grooves being symmetrical with respect to a diametral plane passing therethrough and the grooves adjacent thereto being asymmetrical. 85 90

In testimony whereof we affix our signatures.

BERT R. BENJAMIN.
GEORGE M. MERWIN.
